GRINDING WHEEL DRESSER

Jack C. Potter, St. Louis, Mo.

Application April 18, 1957, Serial No. 653,636

5 Claims. (Cl. 125—11)

This invention relates in general to grinding wheel dressers and, more particularly, to a grinding wheel dresser adapted to be mounted on a surface grinding machine frame for dressing the angle of the edge of the grinding wheel during operation thereof.

Heretofore, various types of dressers have been developed either for dressing the angle of a grinding wheel or for truing same, but the use of such has consistently necessitated temporary discontinuance of productive operation of the machine, with removal of the work, while angle dressing is effected, since such dressers must be specially mounted for use. Obviously, the same have proved most costly in practice, as the time consumed for mounting and dismounting, as well as operation, markedly reduces the effective productive operating time of the grinding wheel and also involves the non-productive services of the operator during such interval.

Thus it is an object of the present invention to provide an angle dresser which may be mounted upon the frame of a grinding machine in such position so as to permit continuous or intermittent dressing of the wheel while the same is engaged in grinding operations whereby angle dressing will not necessitate loss of time from production or disturbance of the work.

It is another object of the present invention to provide an angle dresser which is capable of dressing a grinding wheel through a range of substantially 45 degrees.

A further object of the present invention is to provide an angle dresser which is integrated with a protective shield adapted for detachable engagement upon a grinding machine; and which will prevent injury to the operator from removed particles of abrasives.

It is another object of the present invention to provide an angle dresser which is adapted for adjustment for accommodating grinding wheels of varying diameters.

An additional object of the present invention is to provide an angle dresser having a carriage adapted for smooth, sliding travel along the dresser frame to assure easy positionment therealong.

Another object of the present invention is to provide an angle dresser for grinding wheels which may be most economically manufactured; which is durable and reliable in usage; which comprises a simplicity of parts; and which may be easily operated.

These and other detailed objects are obtained by the structures illustrated in the accompanying drawing in which—

Figure 1 is a front view of an angle dresser constructed in accordance with and embodying the present invention illustrating the same as mounted upon the frame of a grinding machine.

Figure 2 is a top plan view of the angle dresser taken along the line 2—2 of Figure 1.

Figure 3 is a front view of the angle dresser as detached from the grinding machine.

Figure 4 is a vertical transverse section taken on the line 4—4 of Figure 2.

2

Figure 5 is a vertical transverse section taken on the line 5—5 of Figure 3.

Referring now by reference characters to the drawing which illustrates the preferred embodiment of the present invention, A designates generally a conventional grinding machine having a frame with a recessed portion within which is rotatably mounted a grinding wheel 1; there being the usual bed 2 for supporting work w. Provided for detachable securement upon the frame of machine A, as by means of retaining screws s, in covering relation to the recess containing wheel 1 is a plate-like shield or closure 3. In mounted position the lower margin of shield 3 will be spaced upwardly of the lower edge of wheel 1 and is downwardly inclined toward one end for extension at an angle to, and below, the transverse center line of wheel 1 for reasons presently appearing. On the lower portion of the outer face of shield 3, for incorporation therewith as a composite unit, is presented a grinding wheel angle dresser B which comprises an elongated frame portion 10 consisting of a side member 4 having its lower edge in alignment with the lower edge of shield 3, being maintained spacedly outwardly from shield 3 by a pair of parallel end members 5, 6 rigid at their inner ends on shield 3. Formed in shield 3 is an enlarged opening 7 having its transverse axis parallel with the lower edge of shield 3; with the bottom margin of opening 7 being aligned with the upper surface of side member 4.

End members 5, 6, side member 4, and the portion of shield 3 opposite said side member 4 define an elongated opening 8 within which is disposed a carriage C for slideable movement therein. Carriage C incorporates a central slide body 9 having preferably polished lateral surfaces for sliding engagement with the adjacent inner faces of side member 4 and shield 3; the upper surface of slide body 9 is in alignment with the upper surface of side member 4. Secured, as by screws d, to the under portion of slide body 9 is a base plate 10 extending laterally beneath the lower surfaces of side member 4 and shield 3 with which the adjacent upper face portions of plate 10 are in contact. Substantially intermediate its length slide body 9 is provided with an upwardly opening cylindrical recess 11 for receiving a complementary pivot 12 (Figure 5) depending from the under surface of a top block 13 disposed for rotative movement upon slide body 9. An adjusting screw 14 projects upwardly through aligned openings 15, 16 in base plate 10 and slide body 9, respectively, for extension into recess 11 for threaded engagement within a tapped opening 17 in pivot 12 for permitting, upon loosening, rotation of top block 13 with respect to slide body 9, and for maintaining, upon tightening, said block 13 in selected, rotated position; it being noted that block 13 may extend through shield opening 7 during rotation.

In its upper surface top block 13 is provided with a dove-tail or undercut groove 18 forming a guideway one side of which is defined by an adjustment plate 19 secured to top block 13 by set screws 20 regulated threading of which allows positioning of said adjustment plate 19 toward and away from block 13 for reasons presented hereinbelow. Slideably disposed within groove 18 is a dressing-point carrier 21 having lateral beveled faces as at 22, 22' for engagement with the sides of said groove 18 and at its outer end is drilled as at 23 for reception of the inner end of a handle 24 by which an operator may cause carrier 21 to be slidably moved reciprocally within groove 18. At its inner end carrier 21 mounts a rod-like point holder 25, axially aligned with handle 24 and carrier 21, which supports adjacent its outer end and on its lateral face the customary dressing tool or diamond-point 26. By adjustment of set screws 20 the pressure against the sides of dressing-point carrier 21 may be varied thereby permitting predetermined control of the

rate of the stroke by which the operator moves carrier 21.

Normally the inner end portion of carrier 21 and point-holder 25 will project inwardly through shield opening 7 for presenting point 26 to the peripheral surface of wheel 1 for dressing or trimming same to the desired angle of bevel by reciprocatory movement imparted by the operator to carrier 21.

Disposed on the upper surface of top block 13 to one side of carrier 21 is a dial or gauge 27 (see Figure 2) having markings graduated thereon, as by inscription, from zero to forty five for indicating the bevel angle to be formed on wheel 1. Secured to base plate 10 is the lower, inturned end of an indicating finger or pointer 28 which projects upwardly, outwardly of side member 4, for cooperation with dial 27 for establishing top block 13 in proper position for development of the desired angle on wheel 1. Thus, if, for example, the working edge of wheel 1 is to be dressed to a 30 degree angle, top block 13 will be rotated, consequent to loosening of screw 14, so that the thirty marker on dial 27 is aligned with, and immediately adjacent, pointed 28. Thereupon adjusting screw 14 is secured to maintain block 13 in such selected position and reciprocal movement of carrier 21 is then effected by hand with a bevel having an angle of 30 degrees being reliably imparted to wheel 1.

Carriage C may be moved longitudinally of the frame of angle dresser B, for accommodation of wheels of varying diameter, by means of a screw 29 threadedly received within a tapped opening 30 in end member 6, having on its outer end a handle or a knob 31 and being at its inner end tapered as at 32 for reception within a shallow recess 33 formed in the confronting end face of slide body 9 of carriage C. Against the opposite end face of carriage C there bears one end of a compression spring 34, the opposite end of which abuts against the inner face of end member 5; guide projections 35, 36 being provided on slide body 9 and end member 5, respectively, for preventing axial displacement of spring 34. Said spring 34 thus resists movement of carriage C pursuant to inward threading of screw 29 and assures return travel of said carriage upon reverse operation of screw 29.

In view of the foregoing, it is to be particularly observed that angle dresser B is so integrated with shield 3 for constituting an element of machine A and is so disposed as to permit dressing of the periphery of wheel 1 during operation thereof upon work w, thus obviating any need whatever for temporary discontinuance of the operation with the attendant costliness in loss of labor and machine time as has been customary with angle dressers heretofore.

Work w is not disturbed during the angle dressing operation and an operator utilizing grinding machine A may either continuously or intermittently, as necessary, dress the angle of wheel 1 to assure that the particular cut being made in work w is uniform.

Carriage C is designed and especially constructed for even travel along the angle dresser frame as by the character of the engaging surfaces and the lack of positive engagement with screw 29 so that the wobbling, uneven effect brought about in the current use of screw shafts threadedly secured to carriages is avoided. Furthermore, the angle dresser B is set at an angle to the transverse center line of grinding wheel 1 so that diamond point 26 will reliably engage said wheel at a point upon its transverse center line whereby proper contact is assured for effecting the requisite bevel. Thus, angle dresser B is disposed with respect to the horizontal at a predetermined angle to compensate for the height thereof for bringing about efficient operation of point 26. Dial surface 27 is presented as a component of angle dresser B and is located for ready viewing by the operator so that the indicated adjustment may be simply done to result in the proper bevel. Shield 3 provides necessary protection so that particles of abrasives being removed by the dressing

operation will not injure the operator. The angle dresser of the present invention thus has a marked simplicity of parts so that the same may be economically manufactured and will be durable and reliable in usage; and which is presented to a wheel for facile use and without disturbance to the work or the operation thereon.

It should be understood that changes and modifications in the formation, construction, arrangement and combination of the several parts of the grinding wheel dresser may be made and substituted for these herein shown and described without departing from the nature and principle of my invention.

Having thus described my invention, what I claim and desire to secure by Letters Patent is:

- 15 1. An angle dresser for grinding wheels having a frame, a rotatably mounted grinding wheel, and a work support bed comprising a plate-like shield for disposition coveringly over the outer upper portion of said grinding wheel, the bottom edge of said shield being spaced upwardly from the work support bed and extending along a line downwardly inclined with respect to the transverse center line of the grinding wheel, an angle dresser frame comprising a side member disposed outwardly of said shield with its bottom margin aligned with the bottom margin of said shield, a pair of parallel end members engaged to the ends of said side member and to said shield whereby said end members, said side member, and the portion of the shield opposite side member define an elongated opening, a carriage disposed in said opening for sliding movement from end to end thereof, means for effecting movement of said carriage, a top block pivotally mounted on said carriage, for rotation within a plane parallel to the upper surface of said side member, said top block having a guideway formed in its upper surface, a point carrier slideably disposed in said groove for reciprocal movement therewith, a point holder projecting from the inner end of said point carrier, a point provided on the outer end portion of said point holder, said shield having an opening, said point holder projecting through the opening in said shield for presenting the point to the periphery of the grinding wheel, and means for maintaining said top block in selected rotated position for addressing said point to the grinding wheel for effecting the desired degree of bevel thereon.
- 20 2. An angle dresser for grinding wheels having a frame, a rotatably mounted grinding wheel, and a work support bed comprising a plate-like shield for disposition coveringly over the outer, upper portion of said grinding wheel, the bottom edge of said shield being spaced upwardly from the work support bed and extending along a line being downwardly inclined with respect to the transverse center line of the grinding wheel, an angle dresser frame comprising a side member disposed outwardly of said shield with its bottom margin aligned with the bottom margin of said shield and a pair of parallel end members engaged to the ends of said side member and to said shield, whereby said end members, said side member and the portion of said shield opposite side member define an elongated opening, a carriage disposed in said opening for sliding movement from end to end thereof, means for effecting movement of said carriage, a top block pivotally mounted on said carriage for rotative movement in a plane parallel to the upper surface of the side member, said top block having a guideway formed in its upper surface, a point carrier disposed in said groove for reciprocal movement therewith, means for adjusting the width of said guideway for controlling the rate of movement of the point carrier therein, a point holder projecting from the inner end of said point carrier in axial alignment therewith, a point provided on the outer end portion of said point holder, said shield having an opening, said point holder projecting through the opening in said shield for presenting the point to the periphery of the grinding wheel, and
- 25
- 30
- 35
- 40
- 45

means for maintaining said top block in selected rotated position for addressing said point to the grinding wheel for effecting the desired degree of bevel thereon.

3. An angle dresser as described in claim 2 wherein a dial having graduated markings is provided on the upper surface of said top block, and an indicator is fixed on said carriage for cooperation with the dial surface.

4. An angle dresser for grinding wheels having a frame and a rotatably mounted grinding wheel, comprising a plate-like shield for disposition coveringly over the outer upper portion of said grinding wheel, the bottom edge of said shield extending along a line downwardly inclined with respect to the transverse center line of the grinding wheel, an angle dresser frame axially parallel to the bottom edge of said shield, comprising a side member disposed outwardly of said shield, a pair of end members engaged to the ends of said side member and to said shield whereby said end members, said side member, and the portion of the shield opposite said side member define an elongated opening, a carriage 10 disposed in said opening for sliding movement from end to end thereof, means for effecting movement of said carriage, a top block pivotally mounted on said carriage, 15

5

a point carrier slideably carried from said top block for axial reciprocal movement, a point holder provided on said point carrier, a point provided on said point holder, said shield having an opening, said point holder projecting through the opening in said shield for presenting the point to the periphery of the grinding wheel.

5. An angle dresser as described in claim 4 wherein means are provided for maintaining said top block in selected rotated position for dressing the point to the grinding wheel for effecting the desired degree of bevel thereon, a dial having graduated markings is provided on the upper surface of said top block for indicating the degree of bevel, and an indicator is fixed on said carriage for cooperation with the dial surface.
